(57)

CLAIM

The ornamental design for a headphones, as shown and described.

DESCRIPTION

FIG. 1 is a front perspective view of headphones showing our new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a left elevational view thereof; and,

FIG. 7 is a right elevational view thereof.

The broken lines immediately adjacent the shaded areas represent the bounds of the claimed design while all other broken lines depict portions of the headphones that form no part of the claimed design.
